ATTORNEY.

UNITED STATES PATENT OFFICE.

BENJAMIN HIRAM JEFFERSON, OF NILES, MICHIGAN.

STORE ARRANGEMENT.

Application filed July 16, 1923. Serial No. 651,743.

To all whom it may concern:

Be it known that I, BENJAMIN H. JEFFERSON, a citizen of the United States, residing at Niles, in the county of Berrien 5 and State of Michigan, have invented certain new and useful Improvements in Store Arrangements, of which the following is a specification.

The invention relates to store arrangements, and has for its object to provide a store arrangement wherein a passage to one side of the store may be easily and quickly formed, which passage communicates with a room at the rear of the store, which is also 10 formed in the same manner as the passage, and preferably by vertically slideable glazed sash, thereby allowing goods on display within the main portion of the store to be easily observed by persons passing through 15 the passage to the room in the back of the store. The arrangement is particularly adapted for use in connection with music stores wherein the entire floor space is used for display purposes during the day, and 20 a concert hall or room is desired for use at night or other times, at which time the goods on display to the outside of the partition are moved into the main portion of the store, and the sash lowered to form the 25 passage way to one side of the store leading to the concert room in the rear of the store.

A further object is to provide a store with an L-shaped partition, thereby forming an entrance passage or hallway to one side 30 of the store in communication with a room at the rear of the store, and to provide said partition with slideable sash whereby said store may be thrown into a single room if so desired during business hours, and utilized 35 as a concert hall at other times with the goods within the main portion of the store plainly visible to persons entering the concert hall and during the course of the 40 concert.

45 A further object is to form the partitions from a plurality of spaced vertically disposed members or posts, between which posts glazed sash are slidably mounted. The sash are provided with means whereby 50 when one sash is pulled downwardly towards closed position, other sash between the same posts are engaged and pulled downwardly by the moved sash.

55 With the above and other objects in view the invention resides in the combination and arrangement of parts as hereinafter set

forth, shown in the drawings, described and claimed, it being understood that changes in the precise embodiment of the invention may be made within the scope of what is 60 claimed without departing from the spirit of the invention.

In the drawing:—

Figure 1 is a horizontal sectional view through a store showing the partition therein, and the entire floor open for displaying goods in the ordinary course of business. 65

Figure 2 is a view similar to Figure 1, showing the store arranged for concert purposes. 70

Figure 3 is a view in elevation of a portion of the partition, showing the glazed sash therein.

Figure 4 is a vertical transverse sectional view taken on line 4—4 of Figure 3. 75

Figure 5 is a detail sectional view taken on line 5—5 of Figure 4.

Referring to the drawing, the numeral 1 designates a store, which is preferably rectangular shaped as shown and 2 the interior 80 thereof. The arrangement hereinafter set forth is particularly adapted for use in connection with music stores, however it is to be understood that it may be used in connection with other kinds of stores if desired. Many music stores from time to time feature concerts by artists for educational and business purposes, and allow the use of the stores for meeting purposes, however where concerts are given it requires 90 a great deal of labor to properly arrange the store and to prevent damage to goods on display, particularly pianos. At the same time it is desirable for all persons attending the concerts to be able to see the 95 various musical instruments, for instance, pianos, graphophones and the like while attending the concert. To accomplish this result an L-shaped partition 3 is disposed within the interior 2 of the store, which L-shaped partition forms an elongated passage 4 at one side of the store, and a concert room 5 at the rear of the store. Persons entering the concert room 5, enter through the door 6, then pass through the 100 passage 4 to the concert room and occupy the seats 7, which may be of any character, for instance chairs, which may be easily removed and stored. The door 6 also forms 105

passage 4 to the concert room and occupy the seats 7, which may be of any character, for instance chairs, which may be easily removed and stored. The door 6 also forms a main entrance for the store during ordinary business hours, at which time the slideable sash 8 and 9 are in raised position, at 110

which time the pianos 10 are arranged in the usual manner to one side of the store. When it is desired to form the concert room and passage, it will be seen that it will only be necessary to lower the sash 8 and 9, which are slidably mounted in grooves 11 and 12 of the spaced posts 13, and as the sash 8 and 9 are provided with glasses 14, it is obvious that persons passing to the concert room 5 may observe the pianos 10, which have been moved into the main portion 15 of the store, and will also be able to observe the pianos and musical instruments while in the concert room or hall 5 at the rear of the store.

It will be seen that the concert hall with a passage leading thereto may be easily and quickly formed by simply lowering the sash 8 and 9 after moving the goods on display from outside the partition, and during business hours the sash can be easily and quickly raised and goods arranged over the entire floor for display purposes. Disposed to one side of the main portion 15 of the store are a plurality of graphophone demonstrating booths 16, into which any of the graphophones 17 may be moved for demonstrating purposes. The front end of the main portion 15 of the store is provided with a display platform 17 adjacent the front windows 18 of the store, on which goods may be placed in the usual manner for display purposes. At one end of the rear portion of the store a stage 19 is provided on which a piano may be placed for concert purposes, or on which a person may stand while delivering a lecture.

Secured to the upper end of the posts 13 are glazed window frames 21, the lower ends 40 of which are provided with inwardly extending flanges 22 with which the upper rail 23 of the sash 8 engages when said sash is pulled downwardly by the engagement of the upper rail 24 of sash 9 with the lower rail 45 25 of said sash 8, therefore it will be seen by simply pulling downwardly on the sash 9 that the sash 8 may be moved to a lowered position against the action of its weights 26, which weights are sufficiently heavy to raise 50 said sash upon an upward movement of the sash 9. Sash 9 is provided with weights 27 for counterbalancing the same, and if so desired locking means may be provided for locking the sash in lowered position.

From the above it will be seen that a store arrangement is provided wherein a store may be easily and quickly converted into a concert hall at the rear of the store with an entrance passage at the side of the

store, and that goods within the main portion of the store will be on display at all times and visible to persons passing through the passage and into the concert room.

The invention having been set forth what is claimed as new and useful is:—

1. The combination with a store, the interior of which is normally one room, of means whereby said store may be converted into a main display portion with a passage leading from the front of the store to a room at the rear of the store.

2. The combination with a store having its interior normally in one room, of an L-shaped partition disposed within said store thereby forming a main display portion and a room at the rear of the store with a passage for communication to the front of the store and to one side of the store.

3. The combination with a store normally having one room, of means whereby a room may be formed at the rear of the store with a passage for communication with the front of the store adjacent one side of the store, and a main display portion, said means comprising an L-shaped partition, said partition being provided with glazed sash.

4. The combination with a rectangular shaped store, of means whereby a room may be formed at the rear of the store with a passage for communication with the front of the store adjacent one side of the store, said means comprising an L-shaped partition, said partition being formed from spaced posts and vertically slidable sash mounted between said posts.

5. The combination with a store, of means whereby said store which is normally one room may be converted into a main display portion, a room at the back of the store and a passage for communication with the front of the store adjacent one side of the store, said means comprising a partition extending inwardly from the front of the store, said partition having its inner portion terminating in a partition extending to one side of the store and spaced from the rear end thereof, said partition being provided with a plurality of vertically movable glazed sash, said sash being slidably mounted between spaced posts, and interengaging means between the sash between the spaced posts whereby upon a downward movement of one of the sash between the posts the other sash between said posts will be moved downwardly to closed position.

In testimony whereof I affix my signature.

BENJAMIN HIRAM JEFFERSON.
